FLOW INTERMITTER

Alexander Boynton, San Antonio, Tex.; Sida S. Martin executrix of said Alexander Boynton, deceased

Application September 29, 1941, Serial No. 412,870

15 Claims. (Cl. 103—245)

My invention relates to flow intermitters for cased wells and deals with the general subject of my Patents, No. 2,262,750, issued November 18, 1941, and No. 2,263,565, issued November 25, 1941, and my application Ser. No. 412,869, filed September 29, 1941.

The principal object is to provide an automatic intermitter installed above ground for the purpose of causing a well to flow at predetermined intervals and during predetermined lengths of time.

Another object is to provide an intermitter for such purpose which will apply pressure fluid force to the producing formation only while the well is flowing, the pressure being withdrawn from the producing formation while the well is building up each head of liquid.

A further object is to control the duration of the flowing operations and the intervals between such operations, independent of gas pressure within the well.

Another object is to enable a well to be flowed at predetermined intervals and during predetermined lengths of time without subjecting the producing formation of the well to any pressure from the air or gas employed to lift the well liquid, this result being accomplished by employing a packer or string of pressure tubing surrounding the flow tubing, the annular space between the two strings of tubing being closed hermetically proximate their extreme ends.

A still further object is to provide a flow intermitter which will cause flow devices to operate more efficiently and without manual control at pressures which may be varied by adjusting the intermitter.

Another object is to conserve natural gas and to lengthen the natural flowing life of oil wells by closing the wells in before or when their gas begins to break through the well liquid and by opening the wells again when they have built up enough gas to flow them.

Another object is to record the number of flowing operations during known intervals.

In accomplishing the foregoing objects, I employ a piston assembly within an aligned assembly of cylinders, one end of the cylinder assembly being connected with a high pressure line and the other end being connected with a low pressure line. The pressure in the low pressure end of the cylinder assembly is constant at any adjustment thereof; while the pressure in the high pressure end varies intermittently from slightly above that of the low pressure end to somewhat below that of the low pressure end. A latch retards the movement of the piston assembly in

both directions, in order that any movement begun will be completed with certainty. A pressure regulator controls the low pressure in one end of the cylinder assembly, while a bleeder is employed to deplete the pressure in the high pressure end of the cylinder assembly until it becomes less than that of the low pressure end. The resulting intermittent difference in pressures acting upon opposite ends of the piston assembly causes it to travel first in one direction and then in the other; thereby operating a plurality of valves and accomplishing the foregoing objects.

The cylinder assembly is adapted to operate five valves which severally control the duration of the flowing period, the intervals between such periods, the admission of pressure fluid into the well, and the withdrawal of pressure fluid from the well, a mechanical counter being actuated by the piston assembly to record the number of flowing operations; all of which will become more apparent from an examination of the following specification and accompanying drawings, in which—

Fig. 1 is a top view of the preferred embodiment.
25 Fig. 2 is a front elevation of the preferred embodiment.

Fig. 3 is a section on the line 3—3, Figs. 2 and 5.
30 Fig. 4 is a top view of the platform and four valves.

Fig. 5 is a section on the line 5—5, Fig. 2.
35 Fig. 6 is a partial enlarged section through one end of the latch.

Fig. 7 is a top view of a modified form of the platform and valves mounted upon it in Fig. 8.

Fig. 8 is a partial front view of a modified form showing the tubing valve operated by a rack and pinion.

Fig. 9 is a perspective view of the piston bracket.

Fig. 10 is a perspective view of the tubing valve lever.

Fig. 11 is a section on the line 11—11, Fig. 8.
45 Fig. 12 is a 45 degrees elevation of a modified form of the intermitter shown in Fig. 2 with the piston and cylinders perpendicular.

Fig. 13 is a partial top view of the intermitter shown in Fig. 12.

Similar characters of reference are employed to designate similar parts throughout the several views.

The casing head 3 is employed to form a hermetic seal between the well casing 1 and the flow tubing 2, proximately above the ground surface 4, the tubing being positioned centrally within the

casing and being surrounded by the annular space 1a.

A nipple 2a, which is an extension of the tubing 2, is shown connected to the tubing by the union 2b which is employed for convenience in assembling the intermitter and removing it from the well. The bent nipple 5, threadedly connected with the tubing valve 6, may be joined to a flow line leading to a production tank.

The cylinder assembly consisting of the cylinder spacer member 21, having the external longitudinal reinforcing ribs 21b and the high and low pressure cylinders 16 and 19, respectively, is secured upon the nipple 2a by the bolts 42 and 42' which are received through openings in the clamps 41 and 41'.

The two bolts 42' are engaged threadedly with in the two bosses 21g of the cylinder spacer member 21; while the two bolts 42 are received through openings in the supporting flange 21f to which flange these bolts are locked by the nuts 42b. The heads of the bolts 42 and the nuts 42b are beveled as at 42a, Fig. 11, these beveled surfaces being received within conforming countersinks within the supporting flange 21f of the cylinder spacer member 21 for the purpose of rigidly securing the bolts 42 centrally within the openings through the flange.

The tubing valve 6, shown connected between the nipples 2a and 5, has the conventional square operating shank 6a through which the usual lubricator screw 6b extends. The valve 6 may be of the ordinary lubricated plug valve type adapted to open by approximately 90 degrees clockwise swing of the operating handle or lever and to close by a reciprocatory movement.

The tubing valve operating lever 7 (see Fig. 10), which may be pressed over or otherwise secured upon the shank 6a of the valve 6 has an irregular slot 7' within which the actuator pin 8 is positioned. The actuator pin 8 is received closely within the opening 9a of its bracket 9 where it may be secured by the set screw 11 (see Fig. 9). The bracket 9 is secured to the piston member 12 by the studs 18 and 18' engaging within the enlargement 12b of one of the ribs 12a, these ribs having large clearance within the cylinders 16 and 19. The slot 21c of the spacer member 21 provides that the actuator pin bracket 9 and the lever 7 may be free to travel therein during the movements of the piston member 12, as will be explained later. The valve 6 and the cylinder spacer member 21 are positioned at such distance apart that the lever 7 will have clearance with the upper face of the horizontal rib 12a when this lever is perpendicular during its arcuate swing which is divided evenly on either side of the perpendicular, as appears.

The high pressure cylinder 16 and the low pressure cylinder 19 are aligned axially with the spacer member 21. The cylinder 16 has its flange 16b secured to the flange 21a of the spacer member by the bolts 18, and the cylinder 19 has its flange 19b secured to the flange 21a' of the member 21 by the bolts 20.

The piston member 12 has at one end the piston high pressure head 12e, closely slidably within the high pressure cylinder 16, and has at the other end the low pressure piston head 12e', closely slidably within the low pressure cylinder 19. The piston head 12e has an extension 12f, and the piston head 12e' has a similar extension 12f'. Each of the U cups or other form of packing 13 and 13' and each of the spacer rings 14 and 14' separating these cups, has a central open-

ing which closely receives the extensions 12f and 12f', respectively. The dashpot plunger 15 has threaded connection with the extension 12f and serves to lock together the U cups 13 and the spacer ring 14 and to hold them assembled against the end of the piston head 12e. Likewise, the U cups 13' and the spacer ring 14' are held assembled against the end of the piston head 12e' by the dashpot plunger 15'. The U cups 13, 10 closely slidable within the cylinder 16, face toward the outer end of that cylinder, and the U cups 13', closely slidable within the cylinder 19, face toward the opposite direction. The piston member 12, the U cups 13 and 13', the spacer rings 14 and 14', and the dashpot plungers 15 and 15' will be known as the piston assembly.

The cylinder 16 has an end extension forming the dashpot cylinder 16a which is closed at its outer end by the dashpot cap 17. The cylinder 20 19 has a similar end extension forming the dashpot cylinder 19a which is closed at its outer end by the similar cap 17'.

The dashpot plunger 15 is tapered slightly, as appears in Fig. 3, and has very slight clearance, 25 such as one-sixty-fourth inch, within the dashpot cylinder 16a whenever it engages upon the cap 17. Likewise, the dashpot plunger 15', also is tapered slightly and has similar clearance within the dashpot cylinder 19a whenever it engages upon the cap 17'.

Proximately below the cylinder spacer member 21, the casing bleeder valve 22, the high pressure casing input valve 24, the high pressure bleeder valve 26, and the high pressure charger 30 valve 28, which may be plug valves, as shown, are secured adjustably upon the platform 38. The valve 22 has its base engaged upon this platform by the U-shaped strap bolts 34, each end thereof passing through the slots 38b and having 35 its nuts tightened against the nether side of the platform 38. In like manner, the valve 24 is secured firmly upon the platform by the strap bolts 37 having their ends engaged through the slots 38b' and being locked by nuts engaging the nether side of the platform. In order to have its upper end level with the upper ends of the valves 22 and 24, the valve 26 is raised by the base 26b upon which it is secured by the strap bolts 35 40 passing through the slots 38c and urging the base 26b firmly upon the platform. In like manner, the base 28b raises the valve 28 so as to have its upper end level with the upper ends of the valves 22, 24, and 26, where the base 28b is secured by 45 the strap bolts 36 having their ends received through the slots 38c'.

The slots 38b, 38b', 38c, and 38c' of the platform 38 are such length that the valves may be positioned adjustably upon the platform in order to 50 provide that the operating levers will be actuated properly by the drive pins. Provision for similar adjustment is made in the modifications, as is apparent.

The platform 38 has the clamp portion 38a 55 mated with the separate clamp 39, similar to the clamps 41 and 41' in Fig. 5, in order to position the platform 38 securely upon the nipple 2a by means of the bolts 40 and 40', Figs. 2 and 5. The openings for these bolts through the clamp portion 38a of the platform 38 preferably should be countersunk as at 42a, Fig. 11, to receive the beveled head or nut of each of the bolts 40 and 40'.

It is evident that the clamps 38a, 39, 41 and 75 41' may have an internal tooth spread wide

enough to engage all sizes of tubing which usually are employed in flowing wells.

The valve 22 has its operating shank 22a engaged by the operating lever 23, having the slot 23' within which slot is positioned the drive pin 30. The valve 24 has its operating shank 24a engaged by the operating lever 25, having the slot 25' within which slot is positioned the drive pin 33. The valve 26 has its operating shank 26a engaged by the operating lever 27, having the slot 27' within which slot is positioned the drive pin 31. The valve 28 has its operating shank 28a engaged by the operating lever 29, having the slot 29' within which slot is positioned the drive pin 32.

The drive pins 30, 31, 32, and 33 have their upper ends secured within the enlargement 12c of one of the piston ribs 12a at such distance apart as to cause the levers 23, 25, 27, and 29 to be parallel with each other when the pins 30, 31, 32, and 33 are proximate the extreme ends of the slots, as appears in Fig. 4. The slot 21d of the cylinder spacer member 21 is of such width and length as to permit the drive pins to fully open and close the valves 22, 24, 26, and 28, as will be explained later.

The swing of each of the levers 23, 25, 27, and 29 is divided evenly on either side of a center line extending longitudinally through each valve to which the respective levers are attached.

The valves 6, 24, and 26 open together, while, at the same time, the valves 22 and 28 close, it being possible to adjust such valves to open or close in either direction.

The latch best shown in Figs. 3 and 6 is for the purpose of delaying the movements of the piston member 12 until sufficient energy is exerted upon either end thereof to complete the piston travel in the opposite direction. This latch is similar in operation to the latch described in my co-pending application Serial No. 267,193, filed April 10, 1939.

The latch shell 44 is secured against the spacer member 21 by the latch clamps 55 and 55' engaged with the bosses 21h and 21h', respectively, of the member 21 by the cap screws 55a and 55a', respectively. The ends of the shell 44 are closed by the latch shell caps 45 and 45' which engage upon the packings 50a for the purpose of providing leakproof connections.

Proximate its ends, the latch shaft 46 has the latching recesses 46a adapted to be engaged by the latch balls 47 (see Figs. 3 and 6). The ball riders 48 urge the latch balls inwardly against the latch shaft and against the ball floors 49 by force of the coiled latch springs 52, both ball riders and springs having some clearance within the shell 44. Each of the ball floors 49 may be connected threadedly into the shell and secured in position by the lock rings 49a to cause the latch to engage properly at either end of the travel of the shaft 46. The glands 51 may have threaded connection within the ball floors 49 in order properly to compress the packings 50. The holes 51a provide that the packings may be compressed by means of a special wrench applied through the openings 44a. In operation, if it be desired to engage the latch with its full force, the latch balls 47 will be engaged to the maximum depth of the latching recesses 46a, as shown in Figs. 3 and 6. If, however, less latching force is desired at either or both ends of the latch shaft travel, the members 49 and 49a may be unscrewed farther out of the shell 44 until the latch balls 47 will enter the recesses 46a at proper depth

to produce the desired latching force. It will be understood that the members 45a, 47, 48, 49, 49a, 50, 51, and 52 are duplicated at each end of the latch assembly and that the latch engages in the same manner at each end, it being understood that the latch balls 47 may be caused to engage deeper at one end than at the other end, as stated.

The latch is operated by the movements of the piston member 12, the latch drive pin 43 being secured at one end within the enlargement 12d of the piston member, as appears in Fig. 3 and having its other end engaged within an opening through the latch shaft, as appears in Fig. 6. The slot 44b of the shell 44 and the slot 21e of the cylinder spacer member 21 are somewhat wider than the thickness of the pin 43. These slots register and are of proper length to allow the latch shaft 46 to complete its travel in either direction.

The latch lubricator conduit 53, secured upon the shell 44 by the welds 53a and 53b, provides that, by removing the plug 54, the latch may be filled with a lubricant which will be confined by the packings 50, because the latch shaft 46 remains engaged with this packing during all movements of the latch.

The high pressure supply line 56, having within it the T's 57 and 58 and the valve 24, is connected into the casing head 3; whereby it is placed in communication with the annular space 1a. The second high pressure conduit 60 leads out of the high pressure line 56 at the street L 59, bushed into the T 58. This high pressure conduit 60, having the high pressure charger valve 28 and the charger timing valve 62, which latter preferably should be a needle valve, and the T 61 is connected into the first high pressure conduit 65 at the T 63 by means of the bushing 64. The high pressure conduit 65, having the T 63, connects the high pressure receiver 66 to the high pressure lubricator reservoir 68, the latter having threaded connection with the high pressure cylinder 16.

The high pressure line 56 leads also into the pressure regulator 70, which may be of the type disclosed in Patent No. 2,007,363 which was applied for by me, although any of several other kinds of pressure regulators, now available, may be used.

The pressure regulator 70 should be adjusted to reduce somewhat the pressure of the air or gas discharging into the low pressure conduit 71. This conduit, having the check valve 71a and the T 72, is connected into the low pressure lubricator reservoir 68' which, in turn, is connected into the low pressure cylinder 19. A low pressure branch conduit 73 is connected into the T 72 and with the low pressure receiver 74.

The pressure gauge 67, connected into the high pressure conduit 65, and the similar gauge 67', connected into the low pressure conduit 71, are for the evident purpose of indicating the difference in pressures obtaining within the high and low pressure conduits.

The pressure relief valve 75, which may be similar to that shown in Patent No. 2,055,465 which was applied for by me, should be set to pop off at a pressure only slightly greater than that which the regulator 70 should maintain in the low pressure conduit 71; thus providing that approximately the proper difference in pressures will obtain constantly within the high and the low pressure conduits, even though the pressure regulator 70 should leak some pressure fluid into

the low pressure conduit 71 during times when the regulator should maintain its valve closed.

The high pressure bleeder conduit 76, connected into the T 61, leads out of the high pressure conduit 60 and through the valves 26 and 71 which latter, preferably, should be a needle valve. This valve, when open, discharges pressure fluid to atmosphere; thereby reducing the pressure within the receiver 66 and the conduits 65, 76, and that part of the conduit 60 which is between the valve 28 and the conduit 65, in a manner to be explained later.

The casing bleeder conduit 78 leads out of the casing head 3 and through the valve 22 which valve, when open, discharges pressure fluid out of the annular space 1a to atmosphere.

The valves 6, 24, and 26 are adjusted and installed so that they will be open when the piston member 12 travels from the high pressure end to the low pressure end of its stroke; the piston member then assuming the position shown in Fig. 3. On the same stroke, the valves 22 and 28 will be closed. Obviously, when the piston member 12 travels in the opposite direction, i. e., from the low pressure end to the high pressure end of its stroke, the valves 6, 24, and 26 will be closed, while the valves 22 and 28 will be opened.

Thus, it will be observed that the well flowing operation begins when the low pressure head 12e' of the piston member 12 moves into the low pressure cylinder 19, as appears in Fig. 3. Pressure fluid then is discharged into the annular space 1a within the well casing by the valve 24, while the casing bleeder conduit 78 is closed by the valve 22 and, that, at the same time, the high pressure cylinder 16 is having the pressure within it bled off by the open valve 26; while the valve 28 controlling the flow of high pressure fluid into the conduit 60 is closed in order that the open bleeder valve 26 will operate to reduce the high pressure within the cylinder 16. During this time, the valve 6 is open in order that the well may flow through the tubing 2 and the nipples 2a and 5 when the pressure within the annular space 1a is built up to the proper value. The parts retain the positions shown in Figs. 1 to 6 inclusive until the pressure in the high pressure cylinder 16 is reduced to a predetermined value below that in cylinder 19, at which time the well flowing operation is concluded.

At conclusion of the well flowing operation, the high pressure piston head 12e of the piston member 12 moves into the high pressure cylinder 16. At this time, the casing bleeder valve 22 and the high pressure charger valve 28, which controls the input of pressure fluid into the receiver 66, are open; while the valve 24, controlling the pressure fluid input to the casing, and the high pressure bleeder valve 26, controlling the discharge from the receiver 66, and the tubing valve 6, are closed.

It will be assumed that the latch is set to hold against ten pounds per square inch exerted upon either end of the piston member, i. e., against the piston heads 12e and 12e' with no opposing pressure against the opposite head; ten pounds per square inch more pressure acting upon one head than upon the other being assumed to be sufficient force to cause the piston member 12 to complete its travel in either direction.

The high pressure bleeder timing valve 71 controls the duration of the well flowing operation by governing the length of time required to bleed off pressure fluid from the receiver 66 down to

a value enough less than that obtaining within the receiver 74 to force the piston member to its extreme right position.

The charger timing valve 62 controls the interval between flowing operations by governing the length of time required to build up pressure within the receiver 66 to a value such as will cause the piston member to move to its extreme left position, as in Fig. 3.

By way of illustrating the operation of this intermitter, a well forming problem will be stated and its solution demonstrated.

Problem: The well is to be flowed regularly for one hour at intervals of two hours between the flowing operations, using compressed air or gas under 250 pounds pressure, the cycle being completed in three hours.

Solution: (1) Place 250 pounds, or more, of compressed air or gas into the high pressure line 56. (2) Set the regulator 10 to maintain 200 pounds pressure within the conduit 71. (3) Set the pressure relief valve 75 to pop off at 201 pounds. This will prevent any possible leakage through the regulator from interfering with the operation of the intermitter. (4) Set the charger timing valve 62 so that the pressure within the high pressure receiver 66 will build up to 210 pounds in two hours. This pressure will overcome the 200 pounds of pressure in the receiver 74 acting on the low pressure head 12e' and will drive the piston assembly to the left, operating the tubing valve 6. (5) Set the bleeder timing valve 71 (see Fig. 4) so that it will bleed the pressure out of the receiver 66 from 210 pounds to 190 pounds in one hour, at which time the piston will move to the extreme right. This setting of the bleeder timing valve regulates the duration of each flowing operation. The piston assembly then will return to the left and will re-enter the low pressure cylinder 19, as shown in Fig. 3, completing the operating cycle.

The foregoing solution of the previously stated problem contemplates that the pressure regulator is in perfect working order. If the regulator should leak and the relief valve 75 consequently should control the pressure acting upon the low pressure head 12e', it will be necessary for the pressure acting upon the high pressure head 12e to build up to 211 pounds before the piston assembly will move toward the low pressure cylinder 19.

Obviously, there is no relation between the value of the pressure fluid in the line 56 to that required to operate the intermitter which may be made to operate at any pressure equal to, or less than, the pressure employed to flow the well. The latter pressure is determined by well conditions such as the depth and the volume of liquid and the kind of liquid to be lifted; while the pressures necessary to operate the intermitter may be of any lower values which will afford the necessary differential to actuate the high and low pressure piston heads 12e and 12e'.

The size of the high pressure supply line 56 and the valve 24 may be such as two inches, in order that pressure fluid may be placed quickly into the annular space 1a at beginning of the well flowing operation. The sizes of the conduit 78 and the valve 22 may be also such as two inches, in order that the pressure fluid will be discharged quickly out of the annular space 1a at conclusion of the flowing operation. The sizes of the conduits 60 and 76 and of the valves 26 and 28 may be such as one-half inch. Preferably, the valves 62 and 71 should be needle valves, in

order that they may be adjusted delicately to permit only small volumes of gas to pass through them, because the valve 62 in connection with the valve 26 controls the time limit of each well flowing operation and the valve 77 in connection with the valve 28 controls the time interval between well flowing operations, as was explained previously.

The exhaust gas from the well released through the conduit 78 may be discharged into a pipe line connected to the end of the conduit 78, in order that this exhaust gas then may be utilized for other purposes.

By reference to Figures 2 and 4, it will be observed that the valves 6, 22, and 24 are driven by the levers 7, 23, and 25, respectively. The slot 7' in the lever 7 has the pin driving surfaces 7a, 7b, and 7a' and 7b' (see Fig. 10). The pin driving surface 7a is parallel with the piston member when this member is in its extreme position toward the low pressure cylinder 19, and the pin driving surface 7a' is parallel with the piston member when that member is in its extreme position toward the high pressure cylinder 16. These surfaces 7a and 7a' may be of equal length. They provide that the piston member will travel a predetermined distance in either direction, before the actuator pin 8 will engage the driving surfaces 7b or 7b', by which surfaces this pin is caused to open or to close the valve. This arrangement provides that the piston member will be allowed to develop a certain momentum before encountering the resistance of opening or closing the valve 6. In like manner, the levers 23 and 25 are formed with openings similar to the opening 7' in the lever 7, except that the piston member travels a certain distance before the drive pin 30 encounters the load of the lever 23 and, after traveling somewhat farther, encounters the load of the lever 25 by means of the drive pin 33. In this manner, the valve 23 may be caused to begin opening or closing when the piston member has traveled one inch, and for example, the valve 25 may be caused to begin opening or closing when the piston member has traveled two inches, and the valve 6 may be caused to begin opening or closing when the piston member has traveled three inches. The slots in the levers 27 and 29 may be straight to receive the drive pins 31 and 32 closely therein, because the valves 26 and 28 are comparatively small and, for that reason, may be actuated at the beginning of the piston travel.

The reservoirs 68 and 68' have within them the perforated baffle tubes 69 secured to them by welds as indicated at 69'. These reservoirs may be filled with a lubricant which will follow the piston heads 12e and 12e' and will lubricate the cylinders 16 and 19. This lubricant also fills the dashpot cylinders 16a and 19a; thereby aiding the dashpots to cushion the impacts of the cylinder assembly. The lubricant may be placed within the reservoirs 68 and 68' by removing the gauges 67 and 67'. This lubricant may be withdrawn by removing the drain plugs 16c and 16c', Fig. 2.

Attention is directed to the fact that the valves 6 and 22 and the conduit 78 may be dispensed with under certain well flowing conditions. If it be desired to retain the pressure fluid within the well during the interval between flowing operations, the valve 22 and the conduit 78 may be dispensed with and the casing head opening, having the casing bleeder conduit 78 connected into it, may be closed by a plug. If this be done, the

well might build up enough pressure to cause it to flow and thereby to exceed its allowable production. To prevent such irregular flowing, the valve 6 may be employed.

It should be observed also that both of the valves 22 and 24 may be dispensed with, if the well produces enough gas to flow it or if pressure fluid be provided for the annular space 1a from an external source and it is desired to hold a constant pressure on the producing formation. In this event, the part of the high pressure line 56 between the T 58 and the casing head and the conduit 78 will be eliminated from the construction and both side openings of the casing head and the opening of the T 58, thus vacated by part of the line 56, will be closed by plugs.

The mechanical counter 79, many types of which are available, may be secured upon the boss 21j of the cylinder spacer member 21, where it will be actuated to count the well flowing operations by the finger 80a of the counter actuator member 80 secured between the head of the stud 10 and the bracket 9 (see Fig. 9).

In Fig. 7, illustrating a modified form of platform supporting the valves 22, 24, 26, and 28, these valves are the same as those shown mounted upon the platform 38 in Fig. 4, but they are staggered, so that two of them will be opening while the other two will be closing, as in Figs. 2 and 4, without the necessity of providing two valves made or adjusted to open by having their operating shanks turned in opposite directions.

In Figs. 7, 8, and 11, which show a modified platform construction and means for actuating the tubing valve 6, it will be understood that parts bearing the same reference characters as the similar parts in Figs. 1 to 5, both inclusive, are the same in form and purpose in both constructions.

The rack 88, replacing the pin 8 and the bracket 9 in Figs. 1 and 2, is secured upon the piston member 12 by the cap screws 82 engaging the spacer washers 81 upon the piston enlargement 12b of the piston member 12.

The pinion 89, pressed over or otherwise secured upon the valve operating shank 6a of the valve 6, replaces the valve lever 7 in Figs. 2 and 5. The teeth 88a of the rack 88 are enmeshed with teeth 89a of the pinion 89 in such manner as to remain engaged throughout the travel of the piston member 12 in both directions.

The platform 83, Fig. 7, has the valves 22, 24, 26, and 28 secured upon it. The valve 22 may be welded to its base 84, and the valves 24, 26, and 28 may be secured similarly upon their respective bases 84', 85, and 85'. The valve base 84 is shown secured upon the platform 83 by the bolts 86. The valve base 84' may be secured to the platform 83 by the bolts 86'. The valve bases 85 and 85', likewise, may be secured upon the platform 83 by the bolts 87 and 87', respectively.

It will be observed that the valve bases 85 and 85' are of such height as to support the valves 26 and 28 with their upper ends level with the upper ends of the valves 22 and 24, so that the levers 23, 25, 27, and 29 will be on the same horizontal plane in order that the drive pins 30, 31, 32, and 33, of uniform length, may engage the slots 23', 25', 27', and 29', as appears in Fig. 7; thereby causing the same valve action as in Fig. 4.

The mechanical counter 79, shown in Fig. 8 is, in all respects, the same as the one appearing in Fig. 2, except that in Fig. 8 the counter is actuated by being contacted by the rack 88 on the

travel of the piston member toward the low pressure cylinder, as appears.

That part of the assembly which is necessary to complete the intermitter partially shown in Fig. 8, will be understood as being the same as that shown in the device illustrated in Figs. 1, 2, 3, and 5.

In Figs. 12 and 13, illustrating a modified form of the intermitter shown in Figs. 1, 2, 3, and 5, the conduits indicated by numerals bearing the suffix A will be understood as serving the same purpose as those referred to in the previous embodiment by these numerals without the suffix, which is employed for convenience in identifying the conduits and comparing the operation of one construction with the other.

Parts bearing the same reference characters in Figs. 12 and 13, as in the previous embodiments, will be understood as being identical in form and purpose in both constructions.

The low pressure cylinder 94, having the flange 94a, and the cylinder spacer member 96, having the ribs 96a and the flange 96b, are aligned and secured together by the bolts 97 engaged through the flanges 94a and 96b. The high pressure cylinder 95 has its flange 95a secured to the flange 96c of the spacer member 96 by the bolts 97, whereby the latter cylinder is aligned with the other cylinder 94 and the intermediately connected member 96. The cylinder 95, having its lower end threadedly engaged by the cap 93, will be referred to as the high pressure cylinder. The cylinder 94, having its upper end threadedly engaged by the cap 93', will be referred to as the low pressure cylinder. The members 94, 95, and 96 will be referred to as the cylinder assembly, within which there is installed a piston similar to the member 12 in Fig. 3. The lower end of this piston has the head 12e closely slid- 40 able within the high pressure cylinder, as in the previous embodiments. This head has the extension 12g over which the cup spacer rings 91 and 92 have threaded engagement. One of the annular U cups 90 is housed within an annular peripheral recess of the ring 91, and the other U cup 90 is housed within a similar recess of the ring 92. These U cups 90, which may be substituted by any other suitable form of packing, are slid- 45 able closely within the cylinder 95 and are adapted to be expanded against this cylinder by pressure fluid entering the cylinder through the short conduit 122. The ring 92 has an outer end central opening adapted to receive, with slight clearance, the dashpot piston 93a of the cap 93.

The low pressure cylinder 94 and the cap 93', as well as the upper end of the piston, will be understood as being formed like the lower end of the piston and cylinder assembly described in the preceding paragraph. The piston 12 and the U cups 90, and the rings 91 and 92, together with the corresponding cups and rings installed upon the other end of the piston, will be referred to as the piston assembly.

The distance of the piston travel within the cylinder assembly is such as will actuate the valves, as will be explained later. The cylinder 94 is of such length that the upper end of the piston will remain within it on the downward stroke of the piston. The cylinder 95 is, likewise, of such length that the piston head 12e will remain within it when the upper end of the piston is engaged similarly within the cylinder 94.

The cylinder assembly is secured upon and parallel with the nipples 2a and 5 by the two

10 pairs of similar clamps 114-115 and 117-118. The clamp 114, made in two similar halves, is secured upon the nipple 5 by the bolts 116 which bolts are of proper length to secure the similar mating clamp 115 upon the upwardly projecting central tubular boss of the low pressure cylinder cap 93'. The bolts 116 are of proper length to provide that the distance between the nipple 5 and the cylinder assembly may be adjusted by means of the nuts 116a, as is apparent and as was explained for the similar clamp 41-41' in Fig. 5. The clamp 117, secured upon the nipple 2a and the clamp 118, secured upon the depending central tubular extension of the cap 93, serve to secure the cylinder assembly in alignment with the nipple 2a by means of the bolts 116' and the nuts 116a'.

The tubing valve 6 has the lever 7 engaged upon the operating shank 6a, as in Fig. 2. The slot 7' has positioned within it the actuator pin 123, slideable within the slot 96d of the cylinder spacer member 96, this pin being engaged threadedly within the piston member 12 similar to the stud 10 or 10' in the previous embodiment. The pin 123 actuates the lever 7, as was explained in connection with Figs. 1, 2, 3 and 5.

The platform 113 is secured upon the nipples 2a and 5 by means of clamps and bolts. The upper pair of these clamps 105 and 105' is secured upon the nipple 5 by means of the short bolts 106 and the long bolts 107. The upper end of the platform 113 is positioned at proper distance from the cylinder assembly and parallel therewith by means of the long bolts 107 and the nuts 108. The lower platform clamps 109 and 109' are secured upon the nipple 2a by the short bolts 110 and the long bolts 112. The lower end of the platform 113 is positioned at proper distance from the cylinder assembly and parallel therewith by means of the long bolts 112 and the nuts 111. It is apparent that the distance between the platform 113 and the cylinder assembly may be adjusted by screwing the nuts 108 and 111 inwardly or outwardly, as may be required.

The valves 22, 24, 26, and 28, secured upon the platform 113 by the strap bolts 34, 35, 36, and 37, respectively, are similar valves similarly operated by drive pins secured within the piston member 12 and extending within slots in the attached levers 23, 25, 27, and 29. These valves serve the same purpose as the valves bearing the same reference characters in Figs. 2, 3, and 4.

The high pressure supply line 56A, having connected into it the T 99 and the high pressure valve 24, is connected to the T 104 of the low pressure conduit 71A which latter conduit is connected into the casing head 3; thus affording communication between the line 56A and the annular space 1a, the communication being governed by the valve 24.

The casing bleeder conduit 71A has connection with the annular space 1a by means of being connected into the casing head 3 and also has communication with the bleeder valve 22, by which valve the annular space 1a may be closed or opened to atmosphere.

The low pressure conduit 71A, having connected into it the T 100, the check valve 101, the combination check and globe valve 102, the pressure regulator 103 and the T 104, is placed in communication with the annular space 1a by means of being connected into the casing head 3 and is in communication with the upper end of the piston within the low pressure cylinder.

der 94 by means of being connected into the upper end of the lubricator reservoir 68' which reservoir, in turn, has connection with the cylinder cap 93' (see Fig. 13). The low pressure receiver 74 has connection with the conduit 71A by means of the nipple 124.

The first high pressure conduit 65A, having the cross 98 connected into it, is connected with the receiver 66 and with the lubricator reservoir 68, this reservoir being connected with the lower end of the piston assembly within the high pressure cylinder 95 by means of the short conduit 122 and the cylinder cap 93. The clamp 119 engages about the reservoir 68 and the clamp 120 engages about the cylinder 95. Each of these clamps has an internally threaded boss within which is engaged the adjusting stud 121 adapted to adjust properly the distance between the members 68 and 95 and to secure them together before the short conduit 122 is cut to fit.

The second high pressure conduit 60A, having the valves 28 and 62 connected into it, has connection with the T 99 of the line 56A and with the cross 98 of the conduit 65A.

The high pressure bleeder conduit 76A, having connected into it the valves 26 and 77, has connection with the cross 98 of the high pressure conduit 65A.

The bosses 96e and 96e' of the cylinder spacer 96 provide that the same latch assembly as that shown in the preferred embodiment may be attached and employed for the same purpose as was explained previously.

In briefly describing the operation of this embodiment of the intermitter, it will be understood that high pressure air or gas will be available in the line 56A. This pressure fluid passes through the valve 24 and enters the casing head through the T 104 and the swaged nipple which is shown at the inner end of the conduit 71A when the well is flowing, and is cut off by the valve 24 when the well is not flowing.

The bleeder conduit 78A, having its valve 22 closed while the well is flowing, discharges the surplus pressure fluid left in the annular space 1a at conclusion of the flowing operation when the casing bleeder valve 22 is open.

The high pressure conduit 60A is employed to charge the high pressure receiver with compressed air or gas of the value of that within the line 56A. The high pressure charger valve 28 is closed while the well is flowing and is open during the intervals between flowing operations. The time required to build up the pressure within the receiver 66, after it has been bled down during the flowing operation, is controlled by the needle valve 62, which valve thereby controls the intervals between flowing operations.

The high pressure bleeder conduit 76A has its valve 26 open while the well is flowing and has it closed while the well is not flowing. The needle valve 77 may be opened slightly to allow the pressure fluid within the receiver 66 to bleed down far enough to cause the piston assembly to travel in the direction of the low pressure cylinder 94 by force of the pressure fluid within the low pressure receiver 74. The time required for such bleeding down of the pressure fluid within the high pressure receiver 66 determines the duration of the flowing operation.

The pressure regulator, illustrated generally and indicated at 103, is employed to reduce the pressure of the air or gas from the high pressure line 56A to the low pressure air or gas confined within the receiver 74.

It will be understood that the pressure regulators employed in both constructions herein described may be similar to the regulator disclosed in Patent No. 2,007,363, application for which patent was made by me.

The difference between the value of the high pressure within the receiver 66 and the low pressure within the receiver 74 provides that the piston assembly will be forced to its uppermost position within the low pressure cylinder 94 by the high pressure fluid within the receiver 66 and then will be returned to its lowermost position within the high pressure cylinder 95, as shown in Fig. 12, by the pressure fluid within the receiver 74 after the bleeder valve 26 opens and allows the needle valve 77 to drain the pressure fluid slowly out of the receiver 66 down to enough below the value of this fluid within the receiver 74 to allow the latch to be sprung and the piston assembly to be moved downward again by force of pressure fluid from the receiver 74.

The check valve 101 opens to allow flow in the direction of the receiver 74 and closes to prevent compressed air or gas within the receiver 74 from escaping into the well when the casing bleeder conduit 78A is opened by the valve 22 at conclusion of each flowing operation. The combination check and globe valve 102 will have its globe valve open while the intermitter is operative and, like the check valve 101, will have its check valve adapted to open in the direction of the receiver 74.

When the piston assembly moves downward into the high pressure cylinder 95, as shown in Fig. 12, the valves 6, 24, and 26 are open and the valves 22 and 28 are closed. In this operation, the tubing is opened by the valve 6, pressure fluid is placed in the annular space 1a by the valve 24, and the pressure within the receiver 66 is being reduced by the open high pressure bleeder valve 26; while, at the same time, the annular space 1a is shut in by the closing of the valve 22 and pressure fluid is cut off from entering the receiver 66 by the closing of the high pressure charger valve 28. When the pressure within the receiver 66 has been reduced far enough below the pressure within the receiver 74 by the open bleeder valve 26 and the needle valve 77, the piston assembly will be forced upward in which operation the valves 6, 24, and 26 will be closed; while the valves 22 and 28 will be opened. In this operation, the tubing is closed by the valve 6 and the annular space 1a is opened by the valve 22, while the bleeder valve 26 closes to enable the open valve 28 to build up pressure within the receiver 66. During this time, the valve 24 is closed in order to cut off pressure fluid from the well, while the open valve 22 removes all pressure from the producing formations. When the pressure within the receiver 66 builds up through the open valve 28 to a value enough greater than that within the receiver 74, the piston assembly will again move downward and thus the cycle automatically repeats.

It will be noted that the pressure within the receivers 66 and 74 may be of any low value which will afford the differential necessary to operate the piston and valves; while the pressure fluid employed to flow the well may be of any greater value.

Differing from the ordinary combination of clocks and electric appliances usually employed for timing devices, it will be observed that these devices are timed by the valves 62 and 77 by means of which any duration of the flowing

operation controlled by the valve 77 and any interval between such operations controlled by the valve 62, may be obtained as was explained previously.

In Fig. 2, it will be observed that the piston travel is at right angle to the tubing which ordinarily will cause slight vibration; whereas, in Fig. 12, this vibratory effect is overcome by having the piston and tubing aligned.

While the mechanical counter 79 shown in the preferred embodiment is omitted from Fig. 12, it is apparent that such a counter may be secured upon the spacer member 96 and actuated by the pin 123.

Those skilled in the art will know that a packer may be set between the tubing and the casing in combination with a suitable check valve (not shown) in the tubing, in order to prevent the pressure fluid employed in flowing the well from contacting the producing formations of the well.

It is obvious that many minor changes in construction and substitution of other parts for those shown may be made within the scope and purpose of the stated objects and appended claims, and I reserve the right to make such changes and substitutions.

I claim:

1. In a flow intermitter for a well having a casing enclosing a tubing to provide a closed annular space therebetween adapted to receive a pressure fluid, and an outward extension of said tubing: a platform proximate said extension; a valve assembly on said platform comprising a high pressure casing input valve, a casing bleeder valve, a high pressure charger valve, and a high pressure bleeder valve, said high pressure casing input valve and said casing bleeder valve constituting one pair of valves and said high pressure bleeder valve and said high pressure charger valve constituting a second pair of valves, said pairs of valves being arranged so that one valve of each pair opens while the other valve of that pair closes; an operating lever upon each said valve; each of said levers being formed with a slot adapted to receive a drive pin; a cylinder in spaced relation to said platform and valves, said cylinder having a high pressure end and a low pressure end; a piston within said cylinder; drive pins upon said piston, each of said pins being slidale in one of said slots; each end of said cylinder being provided with a dashpot, and complementary structure on the corresponding end of said piston; a latch, an operative connection between said piston and said latch, said latch being adapted to delay and make sudden the movements of said piston; a high pressure lubricator reservoir upon said high pressure end; a low pressure lubricator reservoir upon said low pressure end; a lubricant in said reservoirs; a high and a low pressure receiver proximate said well; a first high pressure conduit between said high pressure receiver and said high pressure lubricator reservoir; a low pressure conduit between said low pressure receiver and said low pressure lubricator reservoir; a high pressure supply line communicating with said annular space, the first said valve being in said supply line; a casing bleeder conduit between said annular space and said casing bleeder valve; a second high pressure conduit between said pressure supply line and said first conduit, said second conduit having said high pressure charger valve and a charger timing valve therein; a high pressure bleeder conduit between said second high pressure conduit and said high pressure bleeder valve, said conduit having a bleeder

timing valve; a branch conduit between said pressure supply line and said low pressure receiver, said conduit having a pressure regulator therein; and a mechanical counter adapted to indicate the successive movements of said piston.

2. In a flow intermitter for a well having a casing enclosing a tubing to provide a closed annular space therebetween adapted to receive a pressure fluid, and an outward extension of said tubing: a valve assembly comprising a high pressure casing input valve, a high pressure charger valve, and a high pressure bleeder valve, the first and third said valves being adapted to open while the second closes; a cylinder in spaced relation to said valves, said cylinder having a high pressure end and a low pressure end; a piston within said cylinder; means upon said piston and valves to open and close said valves by movement of said piston; a latch, an operative connection between said piston and said latch, said latch being adapted to delay and make sudden the movements of said piston; a high and a low pressure receiver proximate said well; a first high pressure conduit between said high pressure receiver and said high pressure end; a low pressure conduit between said low pressure receiver and said low pressure end; a high pressure supply line communicating with said annular space, the first said valve being in said supply line; a second high pressure conduit between said pressure supply line and said first conduit, said second conduit having said high pressure charger valve and a charger timing valve therein; a high pressure bleeder conduit between said second high pressure conduit and said high pressure bleeder valve, said conduit having a bleeder timing valve; and a branch conduit between said pressure supply line and said low pressure receiver, said branch conduit having a pressure regulator therein.
3. In a flow intermitter for a well having a casing enclosing a tubing to provide a closed annular space therebetween adapted to receive a pressure fluid, and an outward extension of said tubing: a valve assembly comprising a tubing valve in said extension, a high pressure charger valve, and a high pressure bleeder valve, said tubing valve and said bleeder valve being adapted to open while said charger valve closes; a cylinder in spaced relation to said valves, said cylinder having a high pressure end and a low pressure end; a piston within said cylinder; means upon said piston and valves to open and close said valves by movement of said piston; a dashpot in each end of said cylinder, and complementary structure on the corresponding end of said piston; a high and a low pressure receiver proximate said well; a first high pressure conduit between said high pressure receiver and said high pressure end; a low pressure conduit between said low pressure receiver and said low pressure end; a second high pressure conduit between said pressure supply line and said first conduit, said second conduit having said high pressure charger valve and a charger timing valve therein; a high pressure bleeder conduit between said second high pressure conduit and said high pressure bleeder valve, said conduit having a bleeder timing valve; and a branch conduit between said pressure supply line and said low pressure receiver, said branch conduit having a pressure regulator therein.
4. In a flow intermitter for a well having a casing enclosing a tubing to provide a closed annular space therebetween adapted to receive a pressure fluid, and an outward extension of said

tubing: a platform proximate said extension; a valve assembly on said platform comprising a high pressure casing input valve, a casing bleeder valve, a high pressure charger valve, and a high pressure bleeder valve, said high pressure casing input valve and said casing bleeder valve constituting one pair of valves and said high pressure bleeder valve and said high pressure charger valve constituting a second pair of valves, said pairs of valves being arranged so that one valve of each pair opens while the other valve of that pair closes; a tubing valve upon said extension, said tubing valve opening simultaneously with said casing input valve; an operating lever upon each said valve; each of said valve operating levers being formed with a slot adapted to receive a drive pin; a cylinder in spaced relation to said platform and valves, said cylinder having a high pressure end and a low pressure end; a piston within said cylinder; drive pins upon said piston, each of said pins being slidably in one of said slots; a dashpot in each end of said cylinder, and complementary structure on the corresponding end of said piston; a latch, said latch being adapted to delay and make sudden the movements of said piston; a high pressure lubricator reservoir upon said high pressure end; a low pressure lubricator reservoir upon said low pressure end; a lubricant in said reservoirs; a high and a low pressure receiver proximate said well; a first high pressure conduit between said high pressure receiver and said high pressure lubricator reservoir; a low pressure conduit between said low pressure receiver and said low pressure lubricator reservoir; a high pressure supply line communicating with said annular space, the first said valve being in said supply line; a casing bleeder conduit between said annular space and said casing bleeder valve; a second high pressure conduit between said pressure supply line and said first conduit, said second conduit having said high pressure charger valve and a charger timing valve therein; a high pressure bleeder conduit between said second high pressure conduit and said high pressure bleeder valve, said conduit having a bleeder timing valve; a branch conduit between said pressure supply line and said low pressure receiver, said branch conduit having a pressure regulator therein; and a mechanical counter adapted to indicate the successive movements of said piston.

5. In a flow intermitter for a well having a casing enclosing a tubing to provide a closed annular space therebetween adapted to receive a pressure fluid, and an outward extension of said tubing: a valve assembly comprising a high pressure casing input valve, a high pressure charger valve, and a high pressure bleeder valve, the first and third said valves being adapted to open while the second closes; a tubing valve upon said extension, said tubing valve being adapted to open and close as said first valve opens and closes; a cylinder in spaced relation to said valves, said cylinder having a high pressure end and a low pressure end; a piston within said cylinder; means upon said piston and valves to open and close said valves; a latch adapted to delay and make sudden the movements of said piston; a high and a low pressure receiver proximate said well; a first high pressure conduit between said high pressure receiver and said high pressure end; a low pressure conduit between said low pressure receiver and said low pressure end; a high pressure supply line communicating with said annular space, the first said valve being in

said supply line; a second high pressure conduit between said pressure supply line and said first conduit, said second conduit having said high pressure charger valve and a charger timing valve therein; a high pressure bleeder conduit between said second high pressure conduit and said high pressure bleeder valve, said conduit having a bleeder timing valve; and a branch conduit between said pressure supply line and said low pressure receiver, said conduit having a pressure regulator therein to reduce the pressure in said low pressure receiver to a predetermined lesser value than the pressure within said high pressure supply line.

15. 6. In a flow intermitter for a well having a casing enclosing a tubing to provide a closed annular space therebetween adapted to receive a pressure fluid, and an outward extension of said tubing: a valve assembly comprising a high pressure casing input valve, a casing bleeder valve, a high pressure charger valve, a high pressure bleeder valve, and a tubing valve, said last valve being adapted to open when said first valve opens, said first and fourth valves opening when said second and third valves close; a high pressure reservoir connected to said high pressure charger and bleeder valves a cylinder in spaced relation to said valves; a piston in said cylinder; means for opening and closing said valves, said means being operable by said piston; a high pressure supply line connected to said casing input valve and communicating via said casing valve with said annular space; a casing bleeder conduit connected to said casing and to said casing bleeder valve; a high pressure conduit connected to said high pressure charger and bleeder valves and to said high pressure reservoir; means connected to one end of said cylinder for maintaining a constant pressure upon one end of said piston; and tubular means connecting said high pressure reservoir to the other end of said cylinder, by virtue of all of which the pressure in said other end of said cylinder is alternately increased and decreased to effect movement of said piston in one direction and then the other, thereby to open and close said valves.

50. 7. In a flow intermitter for a well having a casing enclosing a tubing to provide a closed annular space therebetween adapted to receive a pressure fluid, and an outward extension of said tubing: a valve assembly comprising a high pressure charger valve, a high pressure bleeder valve, and a tubing valve, said last valve being adapted to open as said bleeder valve opens, and to close as said charger valve opens; a cylinder in spaced relation to said valves; a piston in said cylinder; means for opening and closing said valves, said means being operable by said piston; a high pressure conduit connected to said high pressure charger and bleeder valves; means connected to one end of said cylinder for maintaining a constant pressure upon one end of said piston; and tubular means connecting the other end of said cylinder with said charger and bleeder valves, by virtue of all of which the pressure in said other end of said cylinder is alternately increased and decreased above and below, respectively, said constant pressure, thereby to effect movement of said piston in one direction and then the other to operate said valves.

75. 8. In a flow intermitter for a well having a casing enclosing a tubing to provide a closed annular space therebetween adapted to receive a pressure fluid, and an outward extension of said tubing: a platform proximate said extension and parallel

thereto; a valve assembly on said platform comprising a high pressure casing input valve, a casing bleeder valve, a high pressure charger valve, and a high pressure bleeder valve, said high pressure casing input valve and said casing bleeder valve constituting one pair of valves and said high pressure bleeder valve and said high pressure charger valve constituting a second pair of valves, said pairs of valves being arranged so that one valve of each pair opens as the other valve of that pair closes; an operating lever upon each said valve; each of said operating levers being formed with a slot adapted to receive a drive pin; a cylinder parallel to said extension and in spaced relation to said platform and valves, said cylinder having a high and a low pressure end; a piston within said cylinder; drive pins upon said piston, each of said pins being slidable in one of said slots; a latch, an operative connection between said piston and said latch, said latch being adapted to delay and make sudden the movements of said piston; a high pressure lubricator reservoir upon said high pressure end; a low pressure lubricator reservoir upon said low pressure end; a lubricant in said reservoirs; a high and a low pressure receiver proximate said well; a first high pressure conduit between said high pressure receiver and said high pressure lubricator reservoir; a low pressure conduit between said low pressure receiver and said low pressure lubricator reservoir; a high pressure supply line communicating with said annular space, the first said valve being in said supply line; a casing bleeder conduit between said annular space and said casing bleeder valve; a second high pressure conduit between said pressure supply line and said first conduit, said second conduit having said high pressure charger valve and a charger timing valve therein; and a high pressure bleeder conduit between said second high pressure conduit and said high pressure bleeder valve, said conduit having a bleeder timing valve.

9. In a flow intermitter for a well having a casing enclosing a tubing to provide a closed annular space therebetween adapted to receive a pressure fluid, and an outward extension of said tubing; a valve assembly comprising a high pressure casing input valve, a high pressure charger valve, and a high pressure bleeder valve, the first and third said valves being adapted to open while the second closes, said valves being arranged in series parallel to said extension; a cylinder in spaced relation to said valves and parallel with said extension, said cylinder having a high and low pressure end; a piston within said cylinder; means upon said piston and valves to open and close said valves; a latch, an operative connection between said piston and said latch, said latch being adapted to delay and make sudden the movements of said piston; a high and a low pressure receiver proximate said well; a first high pressure conduit between said high pressure receiver and said high pressure end; a low pressure conduit between said low pressure receiver and said low pressure end; a high pressure supply line communicating with said annular space, the first said valve being in said supply line; a second high pressure conduit between said pressure supply line and said first conduit, said second conduit having said high pressure charger valve and a charger timing valve therein; and a high pressure bleeder conduit between said second high pressure conduit and said high pressure bleeder valve, said conduit having a bleeder timing valve.

10. In a flow intermitter for a well having a casing enclosing a tubing to provide a closed annular space therebetween adapted to receive a pressure fluid, and an outward extension of said tubing: a tubing valve on said extension; a charger valve and a bleeder valve in spaced relation to said extension; a cylinder in spaced relation to said valves, said cylinder having a high and low pressure end and being secured parallel and in spaced relation to said extension; a piston within said cylinder; means upon said piston and valves to open and close said valves; a high and a low pressure receiver proximate said well; a first high pressure conduit between said high pressure receiver and said high pressure end; a low pressure conduit between said low pressure receiver and said low pressure end; a second high pressure conduit between said pressure supply line and said first conduit, said second conduit having said high pressure charger valve therein; and a high pressure bleeder conduit between said second high pressure conduit and said high pressure bleeder valve, said conduit having a bleeder timing valve.

11. In a flow intermitter for a well having a casing enclosing a tubing to provide a closed annular space therebetween: a valve in said tubing; a supply of pressure fluid; a conduit between said pressure fluid supply and said closed annular space; a valve in said conduit; a cylinder and piston assembly; conduits connected to opposite ends of said cylinder and to said pressure supply; valves in said last mentioned conduits; and means for effecting cooperation between said valves and between said valves and said piston by virtue of which said valves will all be operated by movement of said piston.

12. In a flow intermitter for a well having a casing enclosing a tubing to provide a closed annular space therebetween: an outward extension of said tubing; a cylinder and piston assembly secured proximate said extension; a valve in said tubing; means to operate said valve from one side of said piston; a supply of pressure fluid; conduits connecting said pressure supply to opposite ends of said cylinder and including valves in spaced relation from said tubing valve; and means to operate said conduit valves from the other side of said piston.

13. In a flow intermitter for a well having a casing enclosing a tubing to provide a closed annular space therebetween: an outward extension of said tubing; a cylinder and piston assembly secured proximate said extension; a valve in said tubing; means to operate said valve from one side of said piston; a supply of pressure fluid; conduits connecting said pressure supply to opposite ends of said cylinder and including valves spaced from said tubing valve; means to operate said conduit valves from the other side of said piston; and latch means carried by said cylinder and piston assembly intermediate said tubing valve and conduit valves for rendering positive and sudden the movements of said piston.

14. In the production of oil from a well including a casing enclosing an eduction tubing to provide a closed annular space therebetween: means for intermittently flowing oil through said tubing which includes means for applying pressure fluid to said space to cause oil to flow through said tubing; means for controlling said flow from and by said applied pressure fluid; and fluid operated means for simultaneously cutting off the flow through said tubing and the application of pressure fluid to said space.

15. In the production of oil from a well including a casing enclosing an eduction tubing to provide a closed annular space therebetween; and a supply of pressure fluid proximate thereto: means for intermittently flowing oil through said tubing which includes means for applying pressure fluid from said supply to said space to cause oil to flow through said eduction tubing; means for

determining the time of and intervals between periods of said flow from said pressure fluid supply; and fluid operated means for simultaneously controlling the flow through said tubing and the application of pressure to said space from and by said pressure supply.

ALEXANDER BOYNTON.
